UNITED STATES PATENT OFFICE.

LYMAN SMITH, OF KANSAS CITY, MISSOURI.

MOUTH-PIECE FOR GRAIN-TRANSFERRING APPARATUS.

SPECIFICATION forming part of Letters Patent No. 289,315, dated November 27, 1883.

Application filed October 2, 1883. (No model.)

To all whom it may concern:

Be it known that I, LYMAN SMITH, of Kansas City, in the county of Jackson and State of Missouri, have invented certain new and useful Improvements in Pneumatic Apparatus for Lifting, Discharging, and Transferring Grain, &c., of which the following is a specification.

The present invention is adapted to the pneumatic system which is described in the following patents: No. 268,303, November 28, 1882, to L. La Rue Smith; No. 268,305, November 28, 1882, to Lyman Smith, and No. 279,034, June 5, 1883, to Lyman Smith. In the system, as described in the said patents, the grain is lifted in the supply or elevating pipe by the production of a partial vacuum in a chamber at the upper end of said pipe, and discharged therefrom by gravity or the weight of the grain.

My present invention consists in a mouth-piece for use at the end of a supply-pipe, and adapted to be conveniently moved about a car or other receptacle and collect the grain there-

25 in contained.

In the drawings, Figure 1 is a perspective view of my improved mouth-piece. Fig. 2 is an enlarged longitudinal section of the same. Fig. 3 is a rear view, partly in transverse sec-

30 tion.

Similar letters of reference indicate similar parts in the respective figures.

A is the mouth-piece, which in practice is made about thirty inches in width across the face a, and with an opening, b, of about one and one-half inch in width. The mouth-piece is preferably made of cast-iron, and at its rear end connects, by a suitable coupling, c, with a six-inch flexible pipe, B, which leads to the 35 stationary grain-supply pipe of the vacuum-chamber of the apparatus, as will be understood by reference to the patents above referred to. Several flexible pipes and mouth-pieces may be used. The under portion of 40 the mouth-piece is provided with an air-chamber, e', leading to bosses e'', cast on the upper part of the mouth-piece. Pipes D are screwed into or secured to the bosses, and constitute air-ducts leading to the chamber e', and through

45 said chamber to the lower part of the front 50 face of the mouth-piece at d. The pipes D are carried up high enough to serve as handles in moving the mouth-piece about the car or other place in collecting the grain. The pipes may be variously curved, so as to conveniently serve the purpose of handles. 55

E is a caster resting and revolving in a socket, e, secured to the under part of the mouth-piece, and serves to support and permit of the movement of the mouth-piece along 60 the floor of the car or other place. It will be understood that as the air is exhausted within the supply-pipe, flexible pipes B, and mouth-piece A, and the grain or other substance therefore carried into the mouth-piece, air received into the pipes D will mix at d with the grain or other substance, such mixture of air being necessary to the proper lifting of the material.

The special advantages of the mouth-piece 70 herein described consist in the means whereby it may be conveniently moved about the floor of the car or other place, and whereby a thorough mixture of air with the grain, &c., may be accomplished, it being apparent that 75 a sheet or body of air of the full width of the grain-inlet is mixed with the grain at the inlet. It is also important that the mixture of air should be below the grain entering the mouth-piece.

The mouth-piece may, without departing 80 from my invention, be variously modified to adapt it to different uses and materials. Thus solid handles may be used and the air admitted to the air-chamber by separate ducts. 85

Having described my invention, I claim—

1. A mouth-piece for a pneumatic lifting device, having a narrow inlet at its face and an air chamber and pipes, substantially as set forth.
2. A mouth-piece for a pneumatic lifting device, combined with a caster or supporting roller, substantially as set forth.
3. A mouth-piece for a pneumatic lifting device, combined with a caster, and moving or controlling handles, substantially as set forth.
4. A mouth-piece for a pneumatic lifting

device, combined with a caster, air-inlet pipes serving as handles, and a flexible pipe-connection, substantially as set forth.

5. A mouth-piece for a pneumatic lifting device, having a narrow inlet at its face, and an air-inlet terminating adjacently to the inlet in an opening or slot of substantially equivalent length, as set forth.

In testimony whereof I have hereunto set my hand and seal this 29th day of September, 1883.

LYMAN SMITH. [L. S.]
